UNITED STATES PATENT OFFICE

HARRY E. NORVIEL, OF ANDERSON, INDIANA, ASSIGNOR TO DELCO-REMY CORPORATION, OF DAYTON, OHIO, A CORPORATION OF DELAWARE

ELECTRIC SWITCH

Application filed July 25, 1927, Serial No. 208,084. Renewed January 13, 1930.

This invention relates to electrical switches for controlling the electrical circuits of an automobile and one of its objects is to simplify the construction of and reduce the cost of manufacture of switches of this type.

Further objects and advantages of the present invention will be apparent from the following description, reference being had to the accompanying drawings, wherein a preferred form of embodiment of the present invention is clearly shown.

In the drawings:

Fig. 1 is a front view of a switch embodying the present invention.

Fig. 2 is a sectional view on the line 2—2 of Fig. 1.

Fig. 3 is a fragmentary back view looking in the direction of arrow 3 in Fig. 2.

Figs. 4 and 5 are sectional views taken respectively on the lines 4—4 and 5—5 of Fig. 2.

Figs. 6 and 7 are fragmentary sectional views taken respectively on the lines 6—6 and 7—7 of Fig. 4.

In the drawings, 20 designates the main supporting plate or mounting bracket of the switch. The bracket 20 is provided with hooked ears 21 which engage angle bars 22 extending along the back of an instrument board 23 and secured thereto in any suitable manner. The bracket 20 is provided with a tubular switch case portion 24 to which is attached a non-conducting switch back 25 carrying tubular rivets 26 which provide switch terminals and which are counterbored at 27 to provide conical surfaces providing the stationary switch contacts. The periphery of the back 25 is notched to receive tangs 28 extending from the tubular portion 24.

The tangs are bent at 29 against the back 25 to secure the same to the part 24.

The bracket 20 supports a dial plate 30 attached thereto by bezel ring 31 having a flat flange 32 in engagement with the bracket 20 and secured thereto by tangs 33 which are bent into notches 34 provided in the bracket 20 and bent against the back side of the bracket. When assembled with the bracket, the dial plate 30 is provided with an aperture 35, the wall of which provides a bearing

for the hub 36 of a lever 37. Lever 37 is provided within the switch case with flanges 38, 39 and 40 which bear against the inside of the dial plate 30 to prevent withdrawal of the handle 37 from the switch case. The handle 37 is provided with inwardly extending tangs 41 adapted to enter rectangular holes 42 in a non-conducting plate 43 which is rotatable about a pin 44 attached to the back 25. As the pin 44 is coaxial with the bearing 35, it is apparent that this pin and bearing cooperate to rotatably support the handle 37 and plate 43. The tangs 41 of the handle 37 pass also into rectangular holes 45 in a non-conducting plate 46 so that the plate 46 will be driven by the handle. The plate 46 is drivingly connected with a contact disc 47 and with a non-conducting plate 48 by rivets 49 along which the plate 47 and the plate 48 are freely slideable. The heads of the rivets 49 limit the separation of the plates 47 and 48 from the plate 46 due to the springs 50. One end of each spring bears against a cup-shaped spring seat member 51 which is received by aligned holes in the plates 43 and 46. The holes in the plate 43 are designated by numeral 52 in Figs. 2 and 5. The springs 50 are each received within a semi-spherical recess provided by a semi-spherical embossed portion 53 providing one of the contacts of the contact plate 47. The contacts 53 are urged by the springs 50 into engagement with the inner surface of the switch back 25 or into engagement with certain of the stationary contacts 27 for the purpose of controlling the lighting circuit of an automobile. If desired, the rivets 49 may be freely slideable through the plate 46 and the heads thereof are received by holes 54 in the plate 43. The disc 48 is journaled upon the pin 44. This construction aids in maintaining concentricity between the plates 43, 46 and the contact plate 47.

The disc 48 supports a contact plate 60 which is drivingly connected with the plate 48 by providing it with notches 61 which receive tangs 62 bent from the plate 60. The plate 60 is provided with notches 63 for clearing the heads of the rivets 49 so that the plate 60 will be insulated from the plate 100.

47. Plate 60 is provided with buttons 64 and 65 providing switch contacts which are engageable with arcuate contact plates 66 and 67 respectively for the purpose of connecting 5 an ignition coil terminal 68 with a battery terminal 69 with which the contact 67 is always connected.

The springs 50 urge the contacts 64 and 65 into engagement with the contacts 66 and 67 10 as well as urging the lighting switch contact 53 into engagement with the lighting circuit stationary contact 27. The handle 37 is movable into five different positions namely: park, off, ignition, dim, on and is resiliently maintained in either of these positions due to the cooperation of the spherical contacts 53 with the conically recessed stationary contacts 27 with which each contact 53 is maintained in engagement by a spring 50. 15 The handle 37 is limited in its movement by the engagement of a lug 70 extending from the plate 43 with either of two stop lugs 71 which are formed by partly punching out and bending portions of a wall 72 of the 20 bracket 20. The wall 72 cooperates with an arcuate wall 73 to enclose an arcuate recess 74 through which the lug 70 moves and into which the lug 71 extends.

The parts of the switch are assembled by 25 making the sub-assembly of the bracket 20, the dial plate 30, and the bezel ring 31. The pin 44 is assembled with the switch back 25. Before the back 25 is attached to the bracket 20, the handle 37 is passed through the dial 30 plate 30 from the inner surface thereof, the hole surrounded by the bearing 35 being large enough to permit movement of the handle through it. Then the plates 43, 46 and parts attached to the plate 46 as shown 35 in Fig. 6 are assembled within the case 24 and are attached to the handle 37 by causing the tangs 41 to extend through the rectangular holes 42 in the plates 43 and 46. Then the switch back 25 is secured to the case 24. The 40 springs 50 not only maintain the movable contacts in engagement with the stationary contacts but also urge the plate 46 toward the plate 43, the plate 43 against the flanges 38, 39 and 40 of the handle and urge these 45 flanges against the inside surface of the dial plate 30. Therefore all end play between these parts is taken up by the spring so that the switch will not be noisy when subjected to vibration.

50 While the form of embodiment of the present invention as herein disclosed, constitutes a preferred form, it is to be understood that other forms might be adopted, all coming within the scope of the claims which follow.

60 What is claimed is as follows:

1. An electric switch comprising, in combination, a pressed sheet metal mounting bracket having a dial plate fixed thereto, said mounting bracket having a cylindrical portion pressed therein substantially perpen-

dicular to said dial plate to form a switch mechanism case integral with said bracket, a stationary switch back carrying terminals and stationary contacts fixed to the rear end of said cylindrical portion, a switch handle having a hub portion journaled within an aperture in said dial plate, two individually insulated rotary contact plates drivingly connected to but insulated from said hub portion, each of said contact plates having contact points arranged to engage certain of said stationary contacts on said switch back. 70 75

2. An electric switch comprising, a stationary casing having a front dial plate and an insulated switch back carrying a series of stationary contacts, a switch handle having a hub portion journaled within an aperture in said dial plate, two rotary contact plates axially spaced apart by an insulating member and both drivingly connected to but individually insulated from said hub portion, each of said contact plates having contact points arranged to engage certain of said stationary contacts. 80 85

3. An electric switch comprising, a stationary casing having a front dial plate and an insulated switch back carrying a series of stationary contacts, a switch handle having a hub portion journaled within an aperture in said dial plate, an insulating block fixed 90 95 to said hub portion, a journal pin coaxial with said hub and supported thereby at one end and supported by said switch back at its other end, an insulated rotary contact plate journaled upon said pin and drivingly connected to said hub, said contact plate having contact points engageable with said stationary contacts. 100

4. An electric switch comprising, a stationary casing having a front dial plate and an insulated switch back carrying a series of stationary contacts, a switch handle having a hub portion journaled within an aperture in said dial plate, an insulating block fixed to 105 said hub portion, a journal pin coaxial with said hub and supported thereby at one end and supported by said switch back at its other end, two individually insulated rotary contact plates journaled upon said pin and both drivingly connected to said hub, each of 110 said contact plates having contact points engageable with certain of said stationary contacts on said switch back. 115

5. An electric switch comprising, a stationary casing having a front dial plate and an insulated switch back carrying a series of stationary contacts, a switch handle having a hub portion journaled within an aperture in said dial plate, an insulating block fixed to 120 said hub portion, a journal pin coaxial with said hub and supported thereby at one end and supported by said switch back at its other end, two individually insulated rotary contact plates journaled upon said pin and both drivingly connected to said hub, each 125 130

of said contact plates having contact points engageable with certain of said stationary contacts on said switch back, and spring means interposed between said insulating block and said contact plates for yieldably urging these elements toward said dial plate and switch back respectively.

5. An electric switch comprising, a stationary casing having a front dial plate and an insulated switch back carrying a series of stationary contacts, a switch handle having a hub portion journaled within an aperture in said dial plate, an insulating block fixed to said hub portion, a journal pin coaxial with said hub and supported thereby at one end and supported by said switch back at its other end, an insulated rotary contact plate journaled upon said pin and drivingly connected to said hub, said contact plate having 10 contact points engageable with said stationary contacts, and a series of coil springs interposed between said insulating block and said contact plate for yieldably urging these elements toward said dial plate and switch back respectively.

6. An electric switch comprising, in combination, a pressed sheet metal mounting bracket having a dial plate fixed thereto, said mounting bracket having a cylindrical portion pressed therein substantially perpendicular to said dial plate to form a switch mechanism case integral with said bracket, a stationary switch back carrying terminals and stationary contacts fixed to the rear end of 15 said cylindrical portion, a switch handle having a hub portion journaled within an aperture in said dial plate, two rotary contact plates axially spaced apart by an insulating member and both drivingly connected to but 20 individually insulated from said hub portion, each of said contact plates having contact points arranged to engage certain of said stationary contacts.

7. An electric switch comprising, in combination, a pressed sheet metal mounting bracket having a dial plate fixed thereto, said mounting bracket having a cylindrical portion pressed therein substantially perpendicular to said dial plate to form a switch mechanism case integral with said bracket, a stationary switch back carrying terminals and stationary contacts fixed to the rear end of 25 said cylindrical portion, movable switch mechanism within said case and having movable contacts, and a switch handle having a hub portion extending through said dial plate and operatively connected with said movable contacts, an insulating block fixed to said hub portion, a journal pin coaxial with said hub and supported thereby at one end, and supported by said switch back at its other end, two individually insulated rotary contact plates journaled upon said pin and both drivingly connected to said hub, each of said 30 contact plates having contact points engage-

able with certain of said stationary contacts on said switch back, and spring means interposed between said insulating block and said contact plates for yieldably urging these elements toward said dial plate and switch back respectively.

8. An electric switch comprising, a stationary casing having a front dial plate and an insulated switch back carrying a series of stationary contacts, a supporting plate spaced from the dial plate and forming part of the said case, a switch handle having a hub portion journaled within an aperture in said dial plate, two axially spaced rotary contact plates drivingly connected to but insulated from said hub portion each of said contact plates having contact points arranged to engage certain of said stationary contacts on said switch back.

9. An electric switch comprising, a casing having a front plate and an insulated switch back carrying a series of stationary contacts, a bracket secured to the plate, a switch handle journaled in said front plate and lying between it and the bracket, and two rotary contact plates axially spaced apart by an insulating member and both drivingly connected to but individually insulated from said handle.

10. An electric switch comprising, a casing having a front plate and an insulated switch back carrying a series of stationary contacts, a bracket supporting the plate and forming part of the casing, a switch handle journaled in said front plate, two rotary contact plates axially spaced apart by an insulating member and both drivingly connected to but individually insulated from said handle, each of said contact plates having contact points arranged to engage certain of said stationary contacts.

11. An electric switch comprising, a casing having a front plate and an insulated switch back carrying a series of stationary contacts, a bracket supporting the plate and forming part of the casing, a switch handle journaled in said front plate, two rotary contact plates axially spaced apart by an insulating member and both drivingly connected to but individually insulated from said handle, each of said contact plates having contact points arranged to engage certain of said stationary contacts.

12. An electric switch comprising, in combination, a pressed sheet metal mounting bracket having a dial plate fixed thereto, said mounting bracket having a cylindrical portion pressed therein substantially perpendicular to said dial plate to form a switch mechanism case integral with said bracket, a stationary switch back carrying terminals and stationary contacts fixed to the rear end of said cylindrical portion, a switch handle having a hub portion journaled within an aperture in said dial plate, two rotary contact plates axially spaced apart by an insulating member and both drivingly connected to but individually insulated from said handle, each of said contact plates having contact points arranged to engage certain of said stationary contacts.

13. An electric switch comprising, a stationary casing integrally formed with a flange to provide an attaching bracket, and having a front dial plate fixed thereto, and an insulated switch back carrying a series of stationary contacts, a switch handle having a hub portion journaled within an aperture

in said dial plate, axially spaced rotary contact plates supported by an insulating member and drivingly connected to but individually insulated from said handle, and each of 5 said contact plates arranged to engage certain of said stationary contacts.

In testimony whereof I hereto affix my signature.

HARRY E. NORVIEL.
